UNITED STATES PATENT OFFICE.

ARTHUR REGINALD ANGUS, OF SPIT ROAD MOSMAN, NEW SOUTH WALES, AUSTRALIA.

RAILWAY SAFE-RUNNING DEVICE.

1,189,226.

Specification of Letters Patent.

Patented July 4, 1916.

Application filed January 18, 1911. Serial No. 603,379.

To all whom it may concern:

Be it known that I, ARTHUR REGINALD ANGUS, a subject of the King of Great Britain, residing at Spit Road Mosman, in the 5 State of New South Wales and Commonwealth of Australia, solicitor, have invented a new and useful Improvement in or Relating to Railway Safe-Running Devices, (C'), of which the following is a specification.

10 This invention relates to train protecting apparatus of the kind wherein a train is adapted on coming into contact with track contacts arranged along a railway track to complete selectively different signaling circuits through signaling apparatus on a train according to the particular track contact with which the train comes into contact. Such apparatus is particularly suitable for 15 train protecting systems in which a train is adapted on effecting contact with a track contact to have different indicating operations thereon according to the particular contacts with which it comes into contact and also to such a system as that according 20 to my application for U. S. Letters Patent Serial No. 603378 of even date herewith wherein a single contacting device on a train is adapted to complete a controlling circuit for operating track instruments to secure its 25 protection, or a particular one of several indicating circuits on the train, according to the particular contact with which the contacting device comes into contact.

According to this invention the contacting 30 means comprises track contacts arranged in line along a track with their operative surfaces arranged in different positions transversely of the track and a contacting device arranged on a train and adapted to come 35 into contact with the track contacts and to be displaced thereby laterally so as to contact with one or other of several contacts relating to different circuits on the train, according to the lateral displacement given 40 to the contacting device by the particular track contact with which it effects contact.

The various features of the invention are 45 hereinafter defined in the claims and in order to explain clearly the invention, an example of contacting means according 50 thereto is illustrated by the accompanying drawings and hereinafter described with reference thereto.

In the drawings:—Figure 1 is a perspec-

tive view of the contacting device and switch 55 box removed from a train, Fig. 2 is a sectional view of the contacting device and switch box together, showing in dotted lines the arrangement of the track contacts, and Fig. 3 is a diagram showing the railway 60 track and track contacts and their disposition in relation to the contacting device.

The contact rod 97 is metallic and is mounted on a pivot as shown within the switch box 99 so as to be adapted to rock laterally therein. On the top of the switch box 99 but insulated therefrom are mounted contacts 106, 105, 104, 103, and 0103, 0104, 0105, 0106, connected electrically to conductor wires 305, 110, 145, 151, 148, 111, 0145 70 and 0305 which form parts of different circuits arranged partly on the train and partly on the track. The upper end 101 of the rod 97 is adapted to effect electrical contact with the contacts in the switch box 75 when displaced from its mid position in which it is normally maintained by springs 100 attached thereto and to the switch box. The lower end of the rod 97 is provided with a roller 98, to minimize friction on the surfaces of the track contacts with which it engages. The dotted lines in Fig. 2 indicate the relative positions of track contacts, the operative surfaces 046, 042, 041, and 040, of 80 which are adapted to displace the contacting device 97 to contact with contacts 0106, 0105, 0104, 0103 respectively and the operative surfaces 40, 41, 42, and 46 of which are adapted to displace the contacting device 97 to contact with contacts 103, 104, 105, and 90 106 respectively. These track contacts have ramped ends to move the contacting device 97 gradually from its mid position to the position to which it is finally displaced by the operative surface of a contact with 95 which it engages and the operative surfaces thereof consist of electrically conductive plates mounted on the non-conductive bodies of the contacts, the contact plates being provided with electrical conductors connecting them in the desired manner with apparatus on the track.

The various parts of the contacting means illustrated in the drawings are numbered in a manner corresponding to that of the 105 switching means described in the specification of my aforesaid application Serial No. 603378 so that it may be readily understood

how the present invention may be applied to and used in conjunction with a train protecting system arranged and adapted to operate in the manner described in the aforesaid specification.

What I claim is:—

1. Railway signaling apparatus comprising electric circuits adapted to be completed through signaling apparatus on a train, track contacts arranged along a railway track and having their operative surfaces located in different positions transversely of said track, and a contacting device on said train adapted to come into contact with said track contacts and to be thereby caused to complete said electric circuits selectively according to the positions transversely of said track of the operative surfaces of said track contacts.
2. Railway signaling apparatus comprising electric circuits adapted to be completed through signaling apparatus on a train, track contacts arranged in line longitudinally of a railway track and having their operative surfaces located in different positions transversely of said track, and a contacting device on said train adapted to come into contact with said track contacts and to be thereby caused to complete said electric circuits selectively according to the positions transversely of said track of the operative surfaces of said track contacts.
3. Railway signaling apparatus comprising electric circuits arranged partly on a train and partly on a railway track, a contacting device on said train movable transversely of said track and means on said track adapted to give said contacting device displacements transversely of said track, said contacting device being adapted to cause the completion of said electric circuits therethrough and through said means on said track selectively according to the displacements given thereto by said means.
4. Railway signaling apparatus comprising electric circuits arranged partly on a train and partly on a railway track, track contacts arranged along a railway track and having their operative surfaces located in different positions transversely of said track, and a contacting device on said train adapted to come into contact with said track contacts and to be thereby caused to complete said electric circuits selectively therethrough and through said track contacts according to

the positions transversely of said track of the operative surfaces of said track contacts.

5. Railway signaling apparatus comprising electric circuits arranged partly on a train and partly on a railway track, track contacts arranged in line longitudinally of a railway track and having their operative surfaces located in different positions transversely of said track, and a contacting device on said train adapted to come into contact with said track contacts and to be thereby caused to complete said electric circuits selectively therethrough and through said track contacts according to the positions transversely of said track of the operative surfaces of said track contacts.

6. Railway signaling apparatus comprising electric circuits adapted to be completed through signaling apparatus on a train, two sets of track contacts arranged in line longitudinally of a railway track, the two sets having their operative surfaces projecting on opposite sides of said line and the contacts of each set being arranged in different positions transversely of said track, and a contacting device on said train adapted to come into contact with said track contacts and to be thereby caused to complete said electric circuits selectively according to the displacements given thereto by the operative surfaces of said track contacts.

7. Railway signaling apparatus comprising electric circuits arranged partly on a train and partly on a railway track, two sets of track contacts arranged in line longitudinally of a railway track, the two sets having their operative surfaces projecting on opposite sides of said line and the contacts of each set being arranged in different positions transversely of said track, and a contacting device on said train adapted to come into contact with said track contacts and to be thereby caused to complete said electric circuits selectively therethrough and through said track contacts according to the displacements given thereto by the operative surfaces of said track contacts.

In testimony whereof I have signed my name to this specification in the presence of two subscribing witnesses.

ARTHUR REGINALD ANGUS.
